(57) **CLAIM**

The ornamental design for a hair color applicator, as shown and described.

DESCRIPTION

FIG. 1 is a top, front, right side perspective view of a hair color applicator showing our new design;

FIG. 2 is a top, front, right side perspective view of the hair color applicator of FIG. 1 at a different angle;

FIG. 3 is a left side view thereof; the right side view being a mirror image thereof;

FIG. 4 is a front elevational view thereof;

FIG. 5 is a top plan view thereof;

FIG. 6 is a bottom plan view thereof;

FIG. 7 is a rear elevational view thereof;

FIG. 8 is a top, front, right side perspective view of a second embodiment of a hair color applicator showing our new design;

FIG. 9 is a top, front, right side perspective view thereof at a different angle;

FIG. 10 is a left side view thereof; the right side view being a mirror image thereof;

FIG. 11 is a front elevational view thereof;

FIG. 12 is a top plan view thereof;

FIG. 13 is a bottom plan view thereof;

FIG. 14 is a rear elevational view thereof;

FIG. 15 is a top, front, right side perspective view of a third embodiment of a hair color applicator showing our new design;
FIG. 16 is a top, front, right side perspective view thereof at a different angle;
FIG. 17 is a left side view thereof; the right side view being a mirror image thereof;
FIG. 18 is a front elevational view thereof;
FIG. 19 is a top plan view thereof;
FIG. 20 is a bottom plan view thereof;
FIG. 21 is a rear elevational view thereof;
FIG. 22 is a top, front, right side perspective view of a fourth embodiment of a hair color applicator showing our new design;
FIG. 23 is a top, front, right side perspective view thereof at a different angle;
FIG. 24 is a left side view thereof; the right side view being a mirror image thereof;
FIG. 25 is a front elevational view thereof;
FIG. 26 is a top plan view thereof;
FIG. 27 is a bottom plan view thereof;

FIG. 28 is a rear elevational view thereof;
FIG. 29 is a top, front, right side perspective view of a fifth embodiment of a hair color applicator showing our new design;
FIG. 30 is a top, front, right side perspective view thereof at a different angle;
FIG. 31 is a left side view thereof; the right side view being a mirror image thereof;
FIG. 32 is a front elevational view thereof;
FIG. 33 is a top plan view thereof;
FIG. 34 is a bottom plan view thereof; and,
FIG. 35 is a rear elevational view thereof.
The broken lines showing a container in FIGS. 1, 8, 15, 22 and 29 are for purposes of showing environmental structure only and do not form part of the claimed design. The broken lines showing holes along the teeth of the hair color applicator and the broken lines showing threads in FIGS. 1 through 35 are for illustrative purposes only and do not form part of the claimed design.
